UNITED STATES PATENT OFFICE

HARRY C. DREIBUSS AND GEORGE S. CHILES, OF ST. LOUIS, MISSOURI, ASSIGNEES TO
SCULLIN STEEL COMPANY, OF ST. LOUIS, MISSOURI, A CORPORATION OF MISSOURI

TRUCK BOLSTER

Application filed April 9, 1928. Serial No. 268,638.

This invention relates to railway car trucks and bolsters.

In the conventional railway car truck, the bolster has end portions of substantially the same width as the spaces between the columns on the side frame of the truck, so that said columns will bear against the side walls of the bolster and hold the bolster in a position at right angles to the longitudinal axis of the truck. Endwise movement of the bolster relatively to the side frames is prevented by laterally-projecting lugs or column guides on the side walls of the bolster which embrace the columns of the side frames. Due to the fact that said lugs or column guides are cast integral with the side walls of the bolster, it is the general practice to provide the side frames of the truck with relatively wide bolster-receiving openings corresponding in width to the overall width of the bolster including the column guides thereon, so as to permit the bolster to be taken out of the truck by removing the bolster-supporting springs, then dropping the bolster so as to disengage the lugs or guides on the side walls of same from the columns of the truck side frames, and then moving the bolster endwise through the large opening in one of the side frames. In addition to necessitating the use of side frames provided with very wide bolster-receiving openings, integral lugs or column guides of the kind referred to add considerably to the weight of the bolster. They also make it necessary to use very wide flasks in the operation of casting the bolster.

In order to overcome the above-described objectionable characteristics of the conventional truck bolster that is now in general use, we have devised a car truck bolster in which the bolster is guided and maintained in proper relationship with the side frames by columns on the side frames that project into vertically-disposed recesses, depressions or guideways formed in the sides of the bolster. In such a structure the side frames need only be provided with bolster-receiving openings of substantially the same width as the bolster, due, of course, to the fact that there are no lateral projections on the side walls of the bolster, and another advantage of such a

structure is that the bolster weighs less than the conventional truck bolster provided with laterally-projecting lugs or column guides. Still another advantage of such a structure is that the bolster columns on the side frames tends to hold the upper end portions of the bolster-supporting springs in properly spaced relation, because said columns project inwardly into the zone occupied by the bolster-supporting springs.

The column-receiving recesses in the sides of the bolster may be of any preferred cross-sectional shape, so long as they comprise surfaces that co-operate with the columns to resist endwise movement of the bolster and maintain the bolster in a position at right angles to the longitudinal axis of the truck, but still permit the bolster to move vertically when the truck is in service. Usually each end portion of the bolster will be provided in its sides with vertically-disposed grooves or channels of substantially the same cross-sectional shape and dimensions as the columns of the side frames and spaced inwardly far enough from the extreme ends of the bolster to permit bolster-supporting springs to be arranged on the outside and on the inside of the columns of each side frame.

Figure 1 of the drawings is a side elevational view of a portion of a car truck and bolster constructed in accordance with our invention.

Figure 2 is a perspective view of one end portion of the bolster.

Figure 3 is a horizontal sectional view of one end portion of the bolster and the columns on one side frame that co-operate with the same.

Figure 4 is a vertical transverse sectional view, taken on the line 4-4 of Figure 3.

Figure 5 is a top plan view of the bolster shown in Figure 3, showing the columns in horizontal cross section.

Figure 6 is an end view of said bolster. Figures 7, 8, 9, 10 and 11 are top plan views, illustrating various other ways of constructing the columns of the side frame and the vertically-disposed recesses in the sides of the bolster that receive the columns; and

Figure 12 is an end view of the bolster illustrated in Figure 11.

In the drawings A designates one of the side frames of a railway car truck. B designates the bolster of said truck and C designates the springs that are arranged under the end portions of the bolster to support the same.

The bolster is guided by two vertically-disposed columns D on each side frame, that are positioned in vertically-disposed grooves, recesses or channels 1 in the sides of the bolster. In the form of our invention shown in Figures 2 to 6, inclusive, the columns D of the side frames are provided with reversely-curved concaved surfaces that co-operate with reversely-curved convexed surfaces of the recesses 1 in the sides of the bolster, the said recesses being located far enough inwardly from the ends of the bolster to permit four sustaining springs to be used under each end portion of the bolster, two springs of each of said groups being arranged on the outside of the columns and the remaining springs of the group being arranged on the inside of the columns, as shown in broken lines in Figures 3 and 5. It will be noted that the opposed columns of each side frame project inwardly into the zone occupied by the bolster sustaining springs, and that said columns are arranged intermediate springs that are located on the inside and on the outside of the columns. Consequently, in such a structure the columns D of the side frames tend to hold the upper end portions of the bolster-supporting springs in properly spaced relation.

A truck bolster of the construction above described not only weighs less than a conventional truck bolster provided with laterally-projecting lugs or column guides, but it has the added advantage that the metal of same is of substantially uniform thickness throughout its entire area, a thing which is very desirable in a cast metal structure and which cannot be obtained in a bolster provided with heavy, laterally-projecting lugs of greater thickness than the side walls of the bolster to which they are integrally connected.

The bolster shown in Figure 7 embodies the same desirable characteristics and features of the bolster shown in Figures 1 to 6 and is designed so as to permit three pairs of springs to be used to support each end portion of the bolster. In the bolster shown in Figure 7, however, the recesses 1 in the sides of the bolster have relatively wide, parallel surfaces α that co-operate with opposed, parallel surfaces on the columns D of the side frames to hold the bolster at right angles to the longitudinal axis of the truck, and said recesses have oppositely inclined surfaces γ that co-operate with similarly-disposed surfaces on the columns to resist endwise movement of

the bolster. In such a structure the two springs constituting each pair of end springs are spaced far enough apart to permit the columns D to project inwardly between the same and the intermediate pair of springs are spaced close together and are arranged between the pairs of end springs, thereby permitting sufficient springs to be used to insure an adequate supporting means for the end portions of the bolster.

Figure 8 illustrates a bolster and side frame columns similar to those shown in Figure 7, except that the surfaces γ of the recesses 1 in the sides of the bolster and the co-operating surfaces of the columns D are curved slightly.

In Figure 9 we have illustrated a bolster whose end portions are designed to co-operate with seven springs arranged so as to form pairs of end springs and an intermediate group comprising three springs that are arranged between the end springs, as shown in dotted lines in said figure. In this structure the columns D of the side frame are convex shaped in horizontal cross section, and the bolster is provided in its sides with concaved, vertically-disposed recesses 1 that receive said columns.

Figure 10 illustrates a bolster whose end portions are designed to co-operate with four springs, the columns D of the side frame being substantially channel-shaped in horizontal cross section, and the vertically-disposed recesses 1 in the sides of the bolster which receive said columns being of similar cross-sectional shape.

Figure 11 of the drawings illustrates a bolster of similar design to the one shown in Figure 7, except that the vertically-disposed recesses in the sides of the bolster are substantially V-shaped in cross section, thus providing straight, oppositely-inclined surfaces γ' that co-operate with straight, oppositely-inclined surfaces on the columns D of the side frame to resist endwise movement of the bolster and also maintain the bolster in a position at right angles to the longitudinal axis of the truck.

If desired, the end portions of the bolster, which are substantially box-shaped in general outline, can be reinforced and strengthened by trusses constructed so as to effectively prevent the top wall of the bolster from cambering or being deflected out of shape by the upward thrusts which the bolster-supporting springs exert on the bottom wall of the bolster, as described in our pending application for patent Serial No. 268,639, filed April 9, 1928. The trusses that we prefer to use for this purpose each comprise one or more pairs of oppositely-inclined or diverging members 2 whose lower ends are attached to the bottom wall 3 of the bolster and whose upper ends are attached to the top wall 4 of the bolster adjacent the points where said

top wall is joined to the side walls 5 of the bolster, as shown clearly in Figure 4. In such a structure the upward thrusts that are exerted on the bottom of the bolster by the 5 springs C will be effectively taken up by the conjoint action of the top wall and side walls of the bolster. The bottom wall of the bolster is preferably cut out or provided with one or more holes, so as to reduce the weight of the bolster, and said holes are surrounded 10 either partially or completely by flanges or ribs 6 that project upwardly from the bottom wall of the bolster and to which the lower ends of the oppositely-inclined braces or truss members 2 are integrally connected. In a bolster of the kind shown in Figures 3 and 15 5, the bottom of each end portion of the bolster is provided with a single center hole surrounded by a rib 6 to which the lower ends of the diverging brace members 2 are connected, but in bolsters of the kind shown in the other figures the bottom of each end portion of the bolster is provided with two holes or cut out portions, each of which is partially surrounded by a rib or flange 6 to which the lower end of one of the diverging brace 20 members 2 is attached. Due to the fact that the upper ends of the diverging braces or truss members 2 are attached to the top wall 25 of the bolster in close proximity to the inner walls of the recesses 1 in the sides of the bolster, said braces or truss members reinforce and strengthen the recessed portions of the side wall of the bolster that receive the 30 columns of the side frames.

Having thus described our invention, what we claim as new and desire to secure by Letters Patent is:

1. In a car truck, the combination of a 40 side frame, a bolster having one of its end portions positioned in an opening in said side frame, columns on the side frame for guiding said bolster, which are spaced apart a distance less than the width of the bolster, and 45 supporting springs for said bolster arranged on the inside and on the outside of said columns.

2. A car truck bolster provided with a hollow end portion, vertically-disposed recesses 50 in the sides of the bolster adapted to receive the columns of the side frame, and a truss in said end portion disposed so as to cause upward thrusts exerted on the bottom wall of the bolster to be taken up by the top wall 55 and side walls of the bolster.

3. A car truck bolster provided with a hollow end portion, vertically-disposed recesses in the sides of the bolster adapted to receive the columns of the side frame, and a truss in 60 the end portion of the bolster comprising oppositely-inclined or diverging members connected at their lower ends to the bottom wall of the bolster and at their upper ends to the top wall adjacent the sides of the bolster.

4. A car truck bolster provided with a hol-

low end portion, vertically-disposed recesses in the sides of the bolster adapted to receive the columns of the side frame, and inclined braces in the end portion of the bolster disposed so as to reinforce and strengthen the 70 recessed side walls of the bolster.
